FIG. 3

FIG. 5

FIG. 6

FIG. 4

FIG. 1 is a perspective view of a picture frame, showing my new design;

FIG. 2 is a front elevational view of the picture frame;

FIG. 3 is a side elevation view;

FIG. 4 is a plan view taken along line 4—4 of FIG. 3;

FIG. 5 is a rear view; and

FIG. 6 is a sectional side elevation view taken along line 6—6 of FIG. 2.

The border area between the two spaced peripheral metal ribs surrounding the central, picture bearing area in FIG. 1 and FIG. 2 is wood grained.

The corner decorations disclosed in broken lines in FIGS. 1 and 2 are similar to the decoration seen in solid lines in the upper right corner.

I claim:

The ornamental design for a picture frame, substantially as shown and described.
